GUSTAVE ARNOLD ANDERSON, OF NEW YORK, N. Y.

COMBINATION LOCK.

Application filed July 10, 1923. Serial No. 650,717.

To all whom it may concern:

Be it known that I, GUSTAVE A. ANDERSON, a citizen of the United States, and a resident of the city of New York, borough of Bronx, 5 in the county of Bronx and State of New York, have invented a new and Improved Combination Lock, of which the following is a full, clear, and exact description.

This invention relates to a combination 10 lock, and has for an object the provision of a lock which from the outside of a door can only be opened by a person knowing the combination.

Another object concerns the provision of 15 a lock having a combination which when operated properly will permit the bolt to be retracted, this mechanism arranged in a casing which on the outside of the door presents no means for removing the casing 20 from the door, such as screws.

A further object concerns the provision 25 of means in a locking device whereby a person on the inside of the door can open the door by retracting the bolt whether he 30 knows the combination or not providing he knows how to manipulate a particular latch disposed on the inner side of the door.

The invention is illustrated in the drawings, of which—

35 Fig. 1 is a side elevation of the lock applied to a door showing a part of the casing broken away, this view being taken from the outside of the door;

Fig. 2 is a section taken on the line 2—2 40 of Fig. 1;

Fig. 3 is a side elevation showing the lock attached to a door with a portion of the casing broken away, this view being from the inside of the door;

Fig. 4 is a section taken on the line 4—4 of Fig. 2;

Fig. 5 is an end elevation of the door with the lock in place;

Fig. 6 is a section taken on the line 6—6 45 of Fig. 4;

Fig. 7 is a detail section taken through the shaft of one of the worm gears illustrating the manner in which it is latched;

Fig. 8 is a section showing the relation of 50 the bolt shaft, the key gears and the worm when the gears have been moved to their alined position with respect to the shaft;

Fig. 9 is a section taken through the lock 55 casing showing a form of spring bolt used in a modification;

Fig. 10 is a side elevation of the casing

partly broken away, showing a modified form of the construction;

Fig. 11 is a section taken on the line 11—11 of Fig. 10; and

Fig. 12 is a detail of a manually operated gear used in a modification.

The forms of the invention shown in the drawings are preferred forms, although it is understood that modifications in the construction and arrangement of the parts and in the character of the materials used may be adopted without departing from the spirit of the invention.

This invention as shown in the drawings 70 in a general sense includes a slidable bolt having a groove therein. Around this bolt are disposed a plurality of gears having inwardly projecting pins associated therewith rotatable in transverse grooves in the 75 bolt and adapted when operated by suitable mechanism, such as manually operable worm gears, to aline the pins on the gears with respect to the longitudinal groove in the bolt, so that in this position of the gears the 80 bolt can be moved longitudinally with respect to the gears. However, whenever the gears are not so disposed as to aline their pins or keys with respect to the longitudinal groove in the bolt, the bolt cannot be moved, 85

especially from the outside of the door. With respect to the inside of the door, the bolt can be moved by releasing a manually operable latch member. This latch member is connected to a slidable bar which is 90 tied in any suitable manner to the gears to hold them in a fixed position with respect to the longitudinal movement until the latch member is released. Therefore, even from the inside of the door, the bolt 95

cannot be operated longitudinally without either depressing the latch member or setting the combination. From a careful consideration of the description and claims hereinafter set forth, in connection with 100 the drawings, other features of the invention will appear.

The preferred form of the invention includes a lock casing formed in two pieces, one of which is formed with an outside face 105 plate 10 and projecting side plates 11 and 12. As shown in the drawings in Fig. 1, the base plate 10 extends beyond the edges of the slot cut in the door. The other piece of the casing is a rear or inside plate 13, which can be screwed to the inner ends of the side 110

dimensions than the slot in the door, securing the inside plate to the other casing member and holding the casing on the door firmly. The fact that the gears are disposed on the inside face prevents a person tampering with the door on the outside from removing the casing. Within the casing there is disposed a slideable bolt 14 having a longitudinal groove 15 therein and a plurality of transverse peripheral grooves such as 16, 17 and 18 (see Fig. 4). Disposed around this bolt, and with especial relation to the transverse grooves 16, 17 and 18, are three gears 19, 20 and 21. Each of these gears is provided with an inwardly projecting pin or key 21^a (see Fig. 6), the inner end of which is adapted to extend into the transverse groove with which that particular gear is associated, and when the gear is rotated to be alined with the longitudinal groove 15 of the bolt. Each of the gears is also provided with a laterally extending hub portion 22 around which a ring element 23 is disposed, and on each ring element is mounted a set screw or detent member 24 which in its rotation is adapted to engage with its respective worm gear. These worm gears are numbered 25, 26 and 27; they mesh with the above-mentioned gears, are mounted on shafts 28, 29 and 30 extending through the front and rear plates of the casing, and on their outer ends are provided with knurled knobs such as 31. On the rear inner face of the casing there are provided in the side plates 11 and 12 slots 32 and 33 (see Fig. 3) to receive the ends of a slideable bar 34, which I show designated as the latch bar. The outer end of this latch bar is provided with teeth 35 with which a pinion 36 meshes. This pinion is mounted within the casing on a pinion shaft 37 and is held in a forward position at all times against the rear plate 13 by a spring 38 which surrounds the inner end of the pinion shaft. The outer end of this pinion shaft 37 is provided with a thumbpiece or knob 39. The outer face of the pinion is provided with a latch pin 40 adapted in the normal position of the pinion 36 to extend into an aperture 41 formed in the plate 13 adjacent the shaft 37. The slideable bar 34, which I call the latch bar, is provided with inwardly extending arms, such as 42 and 43 (see Figs. 1 and 2). These arms extend along the side of the outer gears of the series of gears 19, 20 and 21 to confine the movement of said gears within the casing. In other words, it will be observed that since the series of gears, which I may designate the pinion gears, are confined between the latch arms 42 and 43, and since these latch arms are mounted on the latch bar 34, and since the latch bar meshes with the latch pinion 36, and since the latch pinion has a latch pin 40 which in the normal position of the pinion projects

into the hole in the rear plate, this entire series of elements is prohibited from having any movement until some one presses on the knob 39 against the action of the spring 38 and thereby moves the pinion inwardly so that the latch pin 40 will be removed from the aperture 41 in the rear plate 13. In this event, then the slideable bar can be moved either by turning the thumb nut 39 or by gripping the knob 44 disposed on the inner face of the lock and connected to a shaft 45 extending through the bolt 14 and through both the front plate 10 and the rear plate 13, this shaft having on its front end a thumb knob 46.

The position of the combination gears when the pins are alined with the longitudinal groove in the bolt 14 I call the zero position, and in this zero position it is easily understood that the plate can be slid backward and forward by the manipulation of the knobs 44 and 46 from either side of the casing. On the other hand, when the gears are not in the zero position it will be observed that the bolt cannot be moved except to move it forward, because when the bolt is shot to its extreme forward position, shown in Figs. 1 and 2, then the gears which have been moved therewith necessarily, because they are not in their zero position, have by reason of their engagement with the arms 42 and 43 caused the movement of the latch bar 34 and the rotation of the pinion 36. The rotation of this latch pinion 36 has caused the movement of the pin 40 around to the position shown in Figs. 1, 2 and 3, where it is in alinement with the aperture 41 in the rear plate 13; and at the instant this pin is thus alined with this aperture the spring 38 will shoot the pinion forward to force the pin into the aperture. It will, therefore, be seen that the bolt, after this engagement has occurred between the latch pin and the rear plate, cannot be moved backward until the disengagement of these parts is effected or until the worm gears have been operated to set the pins on the pinion gear to zero position. This setting of the pinion gears, of course, can occur from either the inside or the outside, but in view of the fact that the bolt can be moved very easily from the inside by depressing the latch member, it is invariably only from the outside that the combination mechanism is used to unlock the door.

It will be observed that the shafts 28, 29 and 30 of the worm gear, as illustrated in Fig. 7, are provided with slots or grooves such as 47 on opposite sides, and that spring members 48 having inwardly projecting tips or ribs 49 are adapted to engage therewith. This is for the purpose of temporarily latching the worm gear shafts from half revolution, so that the click made by the engagement and disengagement of these parts can

be heard and felt and so that the person operating the thumb knobs from either side of the casing will be able to tell the extent to which the knobs have been moved.

5 It is, of course, understood that the shaft 45 extending through the bolt and the front and rear plates passes through the front and rear plates through slots 50 and 51 formed therein. It is also to be observed that the 10 rings or sleeves such as 23 formed on the hubs 22 of the pinion gears can be adjusted by means of the set screws 24 so that these set screws can make contact with the worm gears at a later or earlier instant of time and 15 thereby vary the combination.

It is understood that in order to manipulate the combination the worm gears are moved as far as possible in any one direction and then the combination is operated 20 by moving the respective gears each the required number of turns or half turns determined until the pins are alined with the grooves.

As shown in Fig. 9, I have provided a 25 spring 52 within the casing back of the innermost combination gear, which will tend to hold this gear and the other gears in the series forward at all times, the bolt having a sloping face characteristic of spring bolts 30 so that the door can be shut and the bolt will retract a sufficient amount against the action of the spring to permit this shutting of the door but will immediately be moved back to the normal position again by the 35 spring.

A further modification of the construction is shown in Figs. 10, 11 and 12, in which the combination gears are operated by pawl members such as 53 mounted on shafts 54 40 held in one normal position by a spring 55 and movable in the opposite direction by thumb buttons 56, the pawls engaging with the teeth of the gears, such as 57, to operate them and aligning their pins with respect to the groove in the bolt shaft. It 45 will be seen, especially with respect to Figs. 10 and 11, that there are a set of these buttons for each side of the casing but that regardless of which set is operated the combination gears can only be moved in one 50 direction thereby. The gears are reset to their normal position by means of large disks such as 58 which are provided on their inner edges with teeth 59 adapting them to 55 be slid over the respective combination gears. The outer edges of these disks 58 are knurled as at 60 (see Fig. 10), and the diameters of these disks are of a size sufficient to permit just a slight portion thereof 60 to extend through the front and rear plates of the casing so that they can be engaged by the hand of the operator to move the gears in either direction. The depressible buttons 56 are so disposed that by depressing them the pawl members can be moved 65

only a definite distance, so that when depressed any button will insure the movement of the combination gears which it engages only a determined and definite distance.

It will thus be seen that I have provided a relatively simple mechanism for placing the locking and unlocking of a bolt in a door under the domination of a combination mechanism which can be very easily and effectively operated from either side of the door but the operation of which can be eliminated by a person on the inside of the door merely by the depression of a simple latch member, whereupon the operation of the combination mechanism is rendered unnecessary and the bolt can be withdrawn by direct movement.

What I claim is:—

1. A lock construction which includes a 55 slide bolt having a longitudinal groove therein and a plurality of transverse grooves, a plurality of gears embracing said bolt and having inwardly projecting pins thereon adapted to extend into said grooves, a plurality of manually operable gears engaging with the first-mentioned gears for rotating said first-mentioned gears whereby the pins thereon can be brought into alinement with the longitudinal groove, a manually engageable element connected to the bolt permitting its movement forward or back with respect to said gears, when the alinement is effected, a latch bar associated with and connected to the said first-mentioned 100 gears, a latch element operated by the movement of the bar, and means on said latch element to latch with the casing on one side thereof when the bar is moved to a definite position, said latching action between the elements and the casing occurring when the first-mentioned gears are moved forward by the movement forward of the bolt when the pins on said gears are not in alinement with the longitudinal groove.

2. A lock construction which includes a 105 slide bolt having longitudinal and transverse peripheral grooves therein, a plurality of gears surrounding said bolt and having inwardly projecting pins adapted normally to lie in the transverse grooves, means for moving the bolt and the gears forward when the gears are in their normal position, a latch bar engageable with said gears, a latch element on said bar, and means for engaging said latch element when the gears have been moved to their extreme forward position to restrain the bolt and the gears from rearward movement.

3. A lock construction which includes a 115 slide bolt having longitudinal and transverse peripheral grooves therein, a plurality of gears surrounding said bolt and having inwardly projecting pins adapted normally to lie in the transverse grooves,

- means for moving the bolt and the gears forward when the gears are in their normal position, a latch bar engageable with said gears, a latch element on said bar, means for engaging said latch element when the gears have been moved to their extreme forward position to restrain the bolt and the gears from rearward movement, and manually operable means for rotating the gears from either side of the bolt to move the pins on said gears in alignment with the longitudinal groove, whereby the bolt may be withdrawn independently of the retraction of the gears.
15. A lock construction which includes a slideable bolt having longitudinal and transverse peripheral grooves therein, a plurality of gears surrounding said bolt and having inwardly projecting pins adapted normally to lie in the transverse grooves, means for moving the bolt and the gears forward when the gears are in their normal position, a latch bar engageable with said gears, a latch element on said bar, means for engaging said latch element when the gears have been moved to their extreme forward position to restrain the bolt and the gears from rearward movement, and manually operable means for rotating the gears from either side of the bolt to move the pins on said gears in alignment with the longitudinal groove, whereby the bolt may be withdrawn independently of the retraction of the gears, and manually operable means on one side of the bolt for releasing the latch, whereby the bolt and gears can be retracted independently of the means for aligning said pin.
